GB	002453944	4/2009

Primary Examiner — Charles D Hanson*(74) Attorney, Agent, or Firm* — Glass and Associates; Kenneth D'Alessandro; Kenneth Glass(57) **CLAIM**

The ornamental design for a wheelchair hand rim, as shown and described.

DESCRIPTION

FIG. 1 is a front perspective view of the wheelchair hand rim showing the new design;

FIG. 2 is a front plan view of the wheelchair hand rim;

FIG. 3 is a rear plan view of the wheelchair hand rim; and,

FIG. 4 is a side view of the wheelchair hand rim.

Any broken lines within these figures showing the environment is for illustrative purposes only and forms no part of the claimed design.

1 Claim, 4 Drawing Sheets(56)
